CLAIM

The ornamental design for a user interface for computer display, as shown and described.

DESCRIPTION

A portion of the disclosure of this patent document contains material to which a claim for copyright and trademark is made. The copyright and trademark owner has no objection to the facsimile reproduction by anyone of the patent document or the patent disclosure, as it appears in the Patent and Trademark Office patent file or records, but reserves all other copyright and trademark rights whatsoever.

The file of this patent contains at least one drawing executed in color. Copies of this patent with color drawings will be provided by the Patent and Trademark Office upon request and payment of the necessary fee.

FIG. 1 is a front view of a user interface for a computer display; and,

FIG. 2 is a front view of a second embodiment thereof. The broken line drawing of a computer display in both views is for illustrative purposes only and forms no part of the claimed design.
